UNITED STATES PATENT OFFICE.

JOHN STENZEL, JR., OF WINDSOR, COLORADO.

SAFETY DEVICE FOR MOTORS.

Application filed July 20, 1920. Serial No. 397,709.

To all whom it may concern:

Be it known that I, JOHN STENZEL, Jr., a citizen of the United States, residing at Windsor, county of Weld, and State of Colorado, have invented certain new and useful Improvements in Safety Devices for Motors; and I do declare the following to be a full, clear, and exact description of the invention, such as will enable others skilled 10 in the art to which it appertains to make and use the same, reference being had to the accompanying drawings, and to the characters of reference marked thereon, which form a part of this specification.

15 The object of this invention is to provide means for automatically cutting off the supply of power to a motor when the same stops. This is particularly adaptable to use with electric motors, where the same are run 20 for long periods of time and where the current from the main line is cut off and re-stored at intervals. Under these last-mentioned conditions motors are frequently burnt out when the flow of current is re-stored. This is a common occurrence, particularly where motors are used for pumping water for irrigation purposes.

25 Briefly the invention comprises the use of a governor which operates a lever or arm 30 for the purpose of throwing out a switch. In the case of electric motors this switch will be the main switch which supplies the current. In the case of gasoline motors, the switch will cut off the spark so that the engine will not run idle in the event that a power belt or the like has broken.

35 In the drawings:

Fig. 1 represents the invention in use, the view being taken on line 1--1 of Fig. 2.

40 Fig. 2 is an elevation at right angles to the view of Fig. 1, as indicated by arrow 2 of Fig. 1.

Fig. 3 is a section similar to that of Fig. 1 showing the parts in position when the 45 motor is running.

A main power shaft 10 is shown provided with a pulley 12 to receive a belt 14, which in turn passes over a pulley 15 on a second shaft 110. If desired, the shaft 110 might 50 be the main shaft, the pulleys and belt being omitted. The shaft 110 is provided with a governor of known type, comprising balls 16 and springs 18, a collar 20 slidable on the shaft 110 being connected with said springs.

55 A yoke 22 engages in said slidable collar and is integral with an arm 24 pivoted at 25.

This arm 24 has a curved shoulder 124 as shown. The pivot 25 is carried by a main framework 26, having a slot 28, which may be formed by a separate strip 29 of the 60 frame as indicated. The upper portion of the slot 28 has an offset section 30, and an intermediate portion of the slot 28 has an offset section 32. A stop or shoulder 34 is located at the bottom of the slot. A bar 35 65 has one end movable in said slot, the other end being pivoted at 36 to the frame. The swinging end of the bar is adapted to seat in either of the offset slot portions 30 or 32. A spring 38 connected with the bar tends to 70 draw said bar downward. A cable 40 is connected by means of a link 42 with a switch 44, which may be mounted upon the wall or any other suitable support 45, the cable passing over a pulley 46 if the position of the switch requires.

In operation, the bar 35 has a swinging end placed manually in the offset slot portion 30, said bar resting upon the corresponding shoulder 130. In this position the 80 arm 24 does not interfere with said bar 35. The motor is then started up and when under way the bar 35 is then moved into the lower offset portion 32, resting upon the shoulder 132. Under these conditions the 85 arm 24 does not interfere with the bar. So long as the motor is in operation and the shaft 110 is driven, the arm 24 will be withdrawn, as shown in Fig. 3. Should the current be shut off and the motor stopped, or should a drive belt or any other moving part break so that the shaft 110 is no longer rotated, the collar 20 will be forced by the 90 governor to move the arm 24 into the position of Fig. 1 so that the shoulder 124 will push the bar 35 off the shoulder 132 and the spring 38 will jerk said bar down to withdraw the switch. The shoulder 124 is curved 95 as shown in order that mere vibration of the 100 moving parts will not cause the arm 24 to displace the bar 35.

I claim:

1. In combination, a driven shaft, a governor connected therewith, an arm movable 105 by said governor, a frame adjacent said arm and having a seat, a member adapted to rest on said seat when said shaft and governor move, power control means having connection with said member, said arm being 110 adapted to force said member from said seat when the shaft and governor stop, whereby

said member will release said power control.

2. In combination, a driven shaft, a governor connected therewith, a member movable by said governor, a frame having a slot provided with an offset seat adjacent said member, a bar adapted to engage in said seat and adapted to move in said slot, a power control device having connection with 10 said bar, said member being adapted to engage and force said bar from said seat when the shaft and governor cease to move, whereby said bar will release said power control.

3. In combination, a driven shaft, a governor connected therewith, an arm movable 15

by said governor, a frame on which said arm is pivoted, said frame having a slot therein having an offset seat, a bar movable in said slot and pivoted to said frame, said bar being adapted to rest on said seat at its free 20 end when said shaft and governor rotate, said arm being adapted to engage and force said bar from said seat when the shaft and governor cease to rotate, a power control, and a connection between said bar and said 25 control, whereby said control will be released when said bar is unseated.

In testimony whereof I affix my signature.

JOHN STENZEL, JR.
